DESIGN FOR A STRAW HANDBAG

David Lewis, New York, N. Y.

Application March 20, 1937, Serial No. 68,297

Term of patent 3½ years

To all whom it may concern:

Be it known that I, David Lewis, a citizen of the United States of America, residing in city of New York, county of New York, and State of New York, have invented a new, original, and ornamental Design for a Straw Handbag, of which the following is a specification, reference being had to the accompanying drawing, forming part thereof,

Fig. 1 is a front view of a straw handbag showing my new design.

Fig. 2 is a top plan view thereof.

I claim:

The ornamental design for a straw handbag, substantially as shown.

DAVID LEWIS.
